KICKOUT AND HOLD-DOWN DEVICE FOR
FASTENER ATTACHING MACHINESJacob P. Treciokas, Oakville, Conn., assignor to
Scovill Manufacturing Company, Waterbury,
Conn., a corporation of Connecticut

Application December 27, 1951, Serial No. 263,634

6 Claims. (Cl. 218—6)

1

This invention relates in general to fastener attaching machines such as are commonly used in securing buttons or fastener elements to garments or the like, and particularly to a kick-out and hold-down device adapted to be attached and operated with such machine to perform a prior operation on the garment before the fastener elements are attached thereto.

In the manufacture of certain classes of garments, and as a specific example we refer to the manufacture of overalls that customarily are provided with a large patch pocket attached to the face of the bib, the upper end of the pocket is provided with means for fastening or closing the open end of the pocket with the underlying portion of the bib through the use of either separable fastener elements or the conventional tack button and button hole connection. When the patch pocket is attached to the bib it is already provided with one or more button holes or component elements of a snap fastener device, and then it is necessary to attach the complementary fastener element to the bib and in its proper alignment. In order to do this it is first necessary to remove the upper portion of a patch pocket from the setting station of the fastener element on the bib.

Machines for accomplishing the above operation are known as kick-out devices and one form is disclosed in the Huelster Patent No. 2,164,743. While these former kick-out devices of the type disclosed in the Huelster patent were satisfactory for the purpose of moving a portion of the garment out of the path of the setting tool, they also had the fault of moving the garment out of alignment with its previously set position in the machine. This was due to the fact that heretofore the garment had to be held in the machine by the operator and frequently the operator was not strong enough to hold the garment against the kicking action of the kick-out device and, therefore, a slight movement of the garment would cause the fastener part set on the garment to be misaligned or out of registry to its component element set on the pocket part.

It is one of the objects of this invention to provide a device that may be easily attached to a fastener attaching machine and will operate in conjunction with the fastener setting mechanism, first mechanically to hold down the garment upon a support member and then kick out the overlying pocket portion out of line with the setting station of the machine.

With this and other objects in view, this invention consists in the features, combination,

2

details of construction and arrangement of parts which will be first described in connection with the accompanying drawings and then more particularly pointed out in the specification.

3 In the drawings,

Fig. 1 is a side view of a fastener attaching machine showing the kick-out and hold-down device mounted thereon and in retracted position.

Fig. 2 is a plan view taken substantially along the line 2—2 of Fig. 1.

Fig. 3 is a left hand elevational view of the machine showing the hold-down and kick-out mechanism in their advanced position during the period of the fastener setting operation.

15 Fig. 4 is a front elevational view of the machine with the hold-down and kick-out mechanisms in their retracted position as shown in Fig. 1, and,

Fig. 5 is a sectional view to show the details of a hold-down device taken along the line of

20 5—5 of Fig. 2.

It is to be understood that the machine to which this invention is applied may be either a button or snap fastener attaching machine of well known construction. Such a machine consists essentially of a base or bed plate 10 having a curved standard 11 extending upwardly therefrom and supporting a bearing head 12 on its front end. A plunger 13 is slidably mounted in the head 12 and is operated at its upper end by a main oscillating lever 14 secured to and supported on a cross shaft 15 pivoting in spaced lug 16 extending upwardly from the standard 11. The plunger 13 carries a setting die 17 having an element carrier block 18 mounted upon its lower end for receiving a fastener element such as an eyelet stud 19 (see Fig. 4). The stud 19 is held in line with the die 17 by spring operated jaws 20 pivoted in said carrier block and the stud may be fed from a hopper into the carrier block 18 through the usual form of feed chute not shown.

45 Mounted on the bed plate 10 is an anvil 21 supporting an element carrier block 22 on its upper end similar to the carrier block 18 carried by the setting die 17 and movable downwardly thereabout against the influence of a coil spring 23. An element such as an eyelet post 24 complementary to the stud 19 may be fed into the carrier block 22 through a feed track 25 in the usual manner and held on the end of the anvil 21 by spring operated jaws 22a supported in the carrier block 22 preliminary to the fastener setting operation.

The garment illustrated as being operated 50 upon by this machine may be an overall bib 26

to which has been previously attached a patch pocket 27 in the usual manner, as by stitching. It is common practice to have the upper end of the pocket detachably closed by snap fastener elements or tack attached buttons and button holes. As here shown the garment when brought to the machine has already had a fastener element such as a socket 28 and attaching cap 29 secured to the pocket patch.

The purpose of the above described machine is to set a complementary fastener element on the bib part of the garment in line with the socket 28, the position being indicated by the center line X in Fig. 1. The socket 28 will, of course, be complementary to the stud 19 previously mentioned in connection with the plunger 13 and associated setting die 17. In order to set the fastener element upon the bib part of the garment at the position as indicated by the line X it is, therefore, necessary to remove the overlying portion of the patch pocket 27 so that the stud 19 and post 24 can be set upon the bib 26 in the position of line X with no interference. It is, therefore, the purpose of the present invention when applied to the above setting machine to first properly register the garment in the machine, clamp the garment against movement, and then remove the overlying portion of the bib from the setting station ahead of the descending plunger for setting the fastener elements.

In order to support the garment and properly register it preliminary to the fastener setting operation a platform table 30 is provided that is held in elevated position substantially on a plane common with the upper surface of the anvil carrier block 22 and the feed track 25 as by means of support brackets 31 attached to the bed plate 10. As noted in Fig. 2 the table 30 has a central cut-out 32 so as to circumvent the anvil carrier block 22 and yet is close enough to said block to provide ample support for the garment in the area of the setting station. A pair of gauge fingers 33 are slidably mounted on horizontal rods 33a extending laterally from the bearing head 12 of the machine. The lower ends of the fingers 33 are formed with embossed portions 33b against which the upper end of the patch pocket 27 may be engaged for properly registering the garment relative to the setting station of the machine.

In order to hold the garment in the machine a clamping or presser member 34 is provided and located substantially on the center line of the machine and behind the fastener setting station so as to prevent dislocation of the garment when the pocket kick-out members 35 and 36 are moved forwardly. The presser member 34 is located between the pair of kick-out plates or members 35 and 36 of identical construction to be more fully described later. The clamping member 34 is made secure to a cross shaft 37 pivoted in the lower end of a pair of dependent bearing brackets 38 and 39 attached to opposite sides of the standard 11. Oscillating motion is imparted to the clamping member 34 through shaft 37 operated by a lever 40 fixedly secured to the right end of the shaft 37, see Figs. 2 and 4. The free end of the lever 40 is connected to a cushion link 42 which specifically consists of two sections, an upper section 43 and a lower section 44. The upper section 43 is formed with a tubular end 45 to telescopically receive the lower section 44 in the form of a rod. The lower end of section 44 is formed with a yoke 46 connected to the end of the lever 40 as by cross pin 47. The rod portion of the section 44 is formed with a reduced

extension 48 that extends into a counterbore 49 of the upper section 43. A coil spring 50 surrounds the reduced extension 48 to impart the cushion effect to the link 42. The cushion link 5 42 is provided to compensate for the variable thicknesses of the garments operated upon in allowing some give to the clamping member 34.

The upper end of the cushion link 42 is connected to a bell crank lever 51 pivoted to the standard 11 as at 52. Between the pivot point 52 and the point of connection with the link 42 the bell crank 51 is provided with a cam follower roll 53 adapted to engage against the peripheral surface of a cam plate 54 fixedly secured to the right end of the main cross shaft 15 as by set screw 55. Rotation is imparted to the cross shaft 15 by the action of the main lever 14 and through the above described linkage operates the presser member 34 in proper timed relationship to the working parts of the machine. The roller 53 is held in constant engagement with the face of the cam plate 54 by means of a coil spring 56 connected between the outer end of the bell crank lever 51 and the standard 11.

Upon actuation of the lever 14 and through the above described mechanism the clamping member 34 will be carried down from its full line position to the dotted position as shown in Fig. 1 where it will clamp the bib part 26 of the overall against the upper face of the feed track 25.

It is to be noted that the kick-out plates 35 and 36 which straddle the clamping member in normal inactive position are as shown in full line in Fig. 1, and in order to operate these plates in the act of removing the upper end of the patch pocket 27 they must necessarily be brought down to the dotted position as shown in Fig. 1. This first motion of lowering the kick-out plates is imparted thereto by movement of the clamping member 34. This is accomplished through the instrument of a strong leaf spring 58 that is made secure to the clamping member at its point of attachment to the cross pin 37. The leaf spring 58 extends above and lengthwise of the clamp member in a free state and engages against the top of a cross bar 59 that joins the kick-out plates together as an integral unit, as best seen in Fig. 5. When the clamping member 34 is moved down to pressing position the spring 58 by its engagement with the cross bar 59 will resiliently impart the initial downward movement to the kick-out plates 35 and 36.

The mechanism for operating the kick-out plates to advance the same for the purpose of removing the overlying patch pocket is located at the left side as best viewed in Fig. 3. It is to be noted from Figs. 1 and 3 that both kick-out plates 35 and 36 are formed with cam slots 35a and 36a of offset configuration and slidably embraced the cross shaft 37 to which the clamp member 34 is attached. The left kick-out plate 36 is operated from a bell crank lever 60 pivoted to the standard 11 as at 61. The lower end of the bell crank is formed with an elongated slot 62 engaging a stud 63 extending laterally from said kick-out plate 36. The opposite end of the bell crank lever 60 supports a cam roller 64 that engages against the peripheral surface of a cam plate 65 fixedly attached to the opposite end of the main shaft 15 as by set screw 66 similar to the cam plate 54 previously mentioned.

The bell crank 60 is normally tensioned in a clockwise direction to hold the roller 64 against the cam plate 65 and also retract the kick-out plates 35 and 36 by a heavy coil spring 67 con-

nnected between the bell crank lever 60 and the standard 11.

In order to stabilize the cam plates 54 and 65 and provide a stronger connection between said cam plates and the main lever 14 there is provided a cross rod 68 extending through and made secure to the lever 14. The cam plates abut against the opposite ends of this cross rod and are made rigid thereto as by means of screws 69 and 70.

Operation

In the operation of attaching the fastener elements to the bib of an overall garment in line with a complemental element previously set to a patch pocket already attached to the bib, the garment when first brought to the machine will be properly oriented by the operator. For this operation the bib will be laid on the support table 30 with a considerable portion of said bib also resting upon the feed track 25. The upper edge of the patch pocket 27 will be brought into contact with the embossed ends 33b of the gauge fingers 33 and the edge seams of the patch pocket will be lined up with said gauge fingers which will thereby dispose the fastener element 28 on the patch pocket directly in line with the setting station of the machine as indicated by the center line X.

When the garment is thus properly located with respect to the setting station of the machine the mechanism for operating the main lever 14 may be actuated to drive the plunger 13 and setting die 17 downwardly. During the counter-clockwise movement of the main lever 14 as viewed in Fig. 1 both cams 54 and 65 will be carried therewith. This motion of the left cam 54 will first serve to swing the clamping or presser member 34 downwardly in a counter-clockwise direction as viewed in Fig. 1, and clamp the bib 26 against the upper surface of the feed track 25.

The counter-clockwise motion of the clamping member 34 will, through the medium of spring 59, also impart a pivoting action to the kick-out plates 35 and 36 about the pivot 37 and initially lower them to the dotted line position shown in Fig. 1. It will be noted that the front end of each of said plates 35 and 36 are formed with notches 35b and 36b. This initially lowered position will bring the notches 35b and 36b of the kick-out plates in line with the upper edge of the patch pocket 27 and better serve to pick up the edge of the patch pocket. Continued movement of the main lever 14 and its attached cam 65 will actuate the bell crank lever 60 on the left side of the machine and impart a positive advancing motion to both kick-out plates 35 and 36 which latter motion will cause the upper end of the patch pocket 27 to be moved toward the front edge of table 30, as shown in Fig. 3, out of line with the setting station of the machine. The forward substantially straight line motion of the kick-out plates 35 and 36 will be controlled by reason of the shape of the cam slots 35a and 36b in said plates which slots have sliding engagement on the support cross pin 37.

After the presser member 34 and kick-out plates 35 and 36 have performed their respective functions, continued motion of the lever 14 will cause the plunger 13 with its setting die 17 to complete its stroke and secure the fastener element (stud 19 and post 24) upon the bib part of the garment in its proper position to line up with the fastener element 28 on the patch pocket

when the latter is returned to its normal position.

While the form of the invention herewith shown and described embraces a preferred embodiment of the same it is to be understood that the construction may be varied as to mechanical details without departing from the spirit of the invention and the scope of what is claimed.

I claim:

10 1. In combination with a fastener attaching machine having a punch and anvil coacting at a setting station for securing elements of a fastener member together upon a garment in line with a previously applied complemental fastener element on an overlying portion of said garment at the setting station, an oscillating lever for operating said punch, a support table, presser means operated from said oscillating lever for clamping a portion of the garment against said table behind the setting station to hold it in the machine, a kick-out means, and means connected to said lever to operate said kick-out means to remove the overlying portion of the garment out of the area of the setting station, said kick-out means being operative after said clamping means has clamped the garment against said table.

2. In combination with a fastener attaching machine having a punch and anvil coacting at a setting station for securing elements of a fastener member together upon a garment in line with a previously applied complemental fastener element on an overlying portion of said garment at the setting station, an oscillating lever for operating said punch, stationary means attached to the machine for locating the garment in proper relation to the setting station, a support table, presser means operated from said oscillating lever for clamping a portion of the garment against said table behind the setting station to hold it in the machine, a kick-out means, and means connected to said lever to operate said kick-out means to remove the overlying portion of the garment out of the area of the setting station, said kick-out means being operative after said clamping means has clamped the garment against the table.

3. In combination with a fastener attaching machine having a punch and anvil coacting at a setting station for securing elements of a fastener member together upon a garment in line with a previously set fastener on an overlying portion of said garment at the setting station, an oscillating lever for operating said punch, stationary means attached to the machine for locating the garment in proper relation to the setting station, a support table, presser means operated from said oscillating lever for pressing a portion of said garment against said table behind the setting station, and kick-out means straddling said presser means also operated from said lever and serving to remove the overlying portion of the garment out of the area of the setting station, and means causing said presser means to act in advance of the kick-out means so as to maintain said garment stationary against the kick-out impulse imparted to said overlying portion.

4. In combination with a fastener attaching machine having a punch and anvil coacting at a setting station for securing a fastener member upon a garment at a position underneath a complementary overlying portion of the garment, a main lever for operating said punch, a support for supporting said garment in line with the setting station, a presser member behind the setting

station, a kick-out member, a set of cams operating with said lever, and linkage means connecting said presser member and said kick-out member to said cams independently of each other, said cams and linkage means serving to operate sequentially said presser member to clamp the garment upon said support and to move said kick-out member forwardly to displace the overlying portion of the garment during the fastener attaching operation.

5. In apparatus for attaching a fastener member to a garment in registry with cooperating fastener means on an overlying piece of fabric comprising in combination an attaching mechanism, a support for supporting said garment in line with the attaching mechanism, a presser member behind said attaching mechanism for clamping said garment against said support, a kick-out member normally positioned above said support, said kick-out member comprising a pair of spaced plates one positioned each side of said presser member, said presser member having

means to operate the preliminary movement of said kick-out member to lower it in line with said overlying piece of fabric, and means operated by said attaching mechanism, first, to operate said presser member to clamp said garment against said support and, secondly, to advance said kick-out member for displacing said overlying fabric during the fastener attaching operation.

10 6. An apparatus as defined by claim 4 wherein the linkage means between one of the cams and the kick-out member includes a resiliently compressible rod.
